UNITED STATES PATENT OFFICE.

GUSTAVE KOCH, OF NEW YORK, N. Y., ASSIGNOR TO HARRY C. BLYE, OF SAME PLACE.

DESIGN FOR A BOTTLE-STOPPER EXTRACTOR.

SPECIFICATION forming part of Design No. 31,398, dated August 15, 1899.

Application filed July 18, 1899. Serial No. 724,310. Term of patent 14 years.

To all whom it may concern:

Be it known that I, GUSTAVE KOCH, a subject of the Emperor of Germany, residing at New York, in the county of New York and State of New York, have invented and produced a new and original Design for a Bottle-Stopper Extractor, of which the following is a specification, reference being had to the accompanying drawings, forming part thereof, in which—

Figure 1 is an edge view of an extractor incorporating my design. Fig. 2 is a top view of same, and Fig. 3 is a bottom view of same.

The leading feature of my design consists of the form or configuration of the bottle-stopper extractor, substantially as shown in the drawings.

In the drawings, A designates the extractor as a whole, said extractor comprising the handle portion B, the downwardly-deflecting portion C, and the substantially horizontal portion D, the latter having the serrated edges E, substantially as shown. 20

What I claim is—

The design for a bottle-stopper extractor, 25 substantially as shown and described.

Signed at New York, in the county and State of New York, this 17th day of July, A. D. 1899.

GUSTAVE KOCH.
